UNITED STATES PATENT OFFICE

2,436,665

ELECTRIC CIRCUIT INTERRUPTER

William E. Paul, Schenectady, N. Y., assignor
to General Electric Company, a corporation of
New York

Application December 27, 1944, Serial No. 569,943

17 Claims. (Cl. 200—148)

1

My invention relates to electric circuit interrupters, and more particularly to an arc extinguishing structure for electric circuit interrupters which will more efficiently interrupt the circuit than arrangements used heretofore. Specifically my invention is an improvement on my prior Patents 1,805,497 and Reissue 18,257, granted May 19 and November 24, 1931, respectively, and assigned to the same assignee as the present application.

Circuit interrupting devices generally in use today employ what might be termed the "brute force" method of interrupting the circuit. By that is meant that the interrupting contacts are separated indiscriminately so that the arc is permitted to form as it will and then extinguishment thereof is attempted. It is obvious that if in an alternating current circuit the contacts were separated at substantially the zero point of the current wave, little or no arcing would result. For many years attempts have been made to design electric circuit breakers embodying this principle. However, circuit interrupters have only recently begun to be sufficiently consistent in their operation to make the matter of selecting the zero in the current wave important. Furthermore, most of the arrangements for selecting the zero point in the current wave have required such complicated apparatus as to be impractical.

It is an object of my invention to provide a new and improved zero current selector for an electric circuit breaker.

It is another object of my invention to provide an electric circuit breaker which interrupts the current with little or no arcing, which is simple and compact in construction, inexpensive to manufacture and very efficient in operation.

It is another object of my invention to provide a new and improved air blast circuit breaker which interrupts the circuit at substantially the zero point of the current wave of the alternating current circuit to be interrupted.

Still another object of my invention is to provide a new and improved fluid blast circuit interrupter with means for conserving the fluid so that more efficient operation is obtained.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying draw-

2

ings in which Fig. 1 is a view, partly in section, of a circuit interrupter embodying my invention; Fig. 2 is a sectional view taken on line 2—2 of Fig. 1, assuming that Fig. 1 shows a complete structure; Fig. 3 is a sectional view taken on line 3—3 of Fig. 1 assuming that Fig. 1 shows a complete structure; Figs. 4, 5 and 6 are schematic diagrams illustrating successive positions of certain parts of the device embodying my invention during the circuit interrupting operation; Fig. 7 is a perspective view of a number of elements of the circuit interrupter embodying my invention; Fig. 8 is a perspective view partly in section of a portion of the circuit interrupter of Fig. 1, and Fig. 9 is a schematic diagram of a circuit interrupting device illustrating a modification of my invention.

Although it will become apparent as the following description proceeds that my invention is applicable to various types of electric circuit breakers, I have chosen to specifically illustrate my invention in connection with a fluid blast circuit breaker preferably an air blast circuit breaker. Although my invention is also adapted for use with single or polyphase circuit breakers, for the sake of simplifying the drawings I have chosen to illustrate my invention in connection with a single phase circuit breaker.

Referring now to the drawings, there is illustrated an electric circuit breaker including an arc extinguishing structure or chamber generally indicated at 1 within which is mounted a first or main pair of relatively movable contacts comprising a stationary contact generally indicated at 2, and a movable blade-type contact generally indicated at 3. Relatively movable contacts 2 and 3 are essentially current carrying contacts, the contact 2 comprising a plurality of spring biased contact fingers 4 and longer fingers 5. Movable contact 3 is provided with an extension 6 adapted to cooperate with fingers 5, the circuit breaker in the drawings being shown in the partially open position just after the fingers 5 and extension 6 have separated. Any suitable means (not shown) for producing relative movement of contacts 2 and 3 may be provided. Preferably, movable contact 3 is connected to a suitable fluid motor or the like in a manner disclosed and claimed in copending application Serial No. 562,296, Boisseau and Bold, filed November 7, 1944, and assigned to the same assignee as the present application.

The arc extinguishing structure 1 is a box-like structure formed of insulating material comprising side plates 7 and 8, end plates 9 and 10

and plate 11. In order to insure no leakage of air and to increase the electrical creepage path, the plates 7, 8, 9, 10 and 11, as best shown in Figs. 1, 3 and 8, are tongued and grooved and fitted together so as to form a unitary structure held together by bolts 12. Essentially arc extinguishing structure 1 is divided into two chambers 13 and 14, respectively, separated by an insulating partition 15, suitably interrelated with side plates 7 and 8, as is clearly shown in Fig. 8. Communication between chambers 13 and 14 can occur only through a rectangular opening 16 in partition 15, which opening is positioned substantially intermediate the ends of partition 15. Partition 15 is held in place by suitable bolts 17 extending through the side plates 7 and 8 of the arc extinguishing structure 1. Stationary contact 2 is suitably supported in chamber 13 and is engageable by movable contact 3 which extends through an opening 18 in end plate 10.

In order to supply a blast of fluid under pressure in arc extinguishing chamber 1, I have provided a source of fluid generally indicated at 19 which is connected through a blast valve schematically indicated at 20 and a conduit 21 with an opening 22 in plate 11 intermediate the ends of plate 11 and substantially opposite the opening 16 in partition 15. A suitable plate 23, bolts 24, and a gasket (not shown) insure a sealed relationship between the air conduit 21 and the opening 22 in plate 11.

Movable contact 3 is electrically connected to a sliding contact 25 including a plurality of contact fingers 26 biased into contacting engagement by spring means 27. The contact fingers 26 are best shown in Fig. 8 while the spring means are best shown in Fig. 1. When the movable contact 3 is pulled out of opening 18 and consequently free of sliding contact 25, the fingers 26 engage with each other and effectively provide a gate so that fluid under pressure such as air, is prevented from escaping from chamber 13 except through opening 16.

It will be obvious to those skilled in the art that it is difficult to operate a main large blast valve such as 20 with sufficient precision and speed both in opening and closing so that a large quantity of air is not lost unnecessarily during a circuit breaker operation. In order to effect a substantial conservation of this otherwise lost air, I provide an auxiliary air valve that cooperates directly with the contacts and which permits a blast of air to flow only when the contacts have reached the point of separation and which stops the blast just as soon as it is no longer needed. The main blast valve 20 may be operated in the usual manner. This auxiliary valve is illustrated in the drawings as a slide valve 28 comprising a rectangular plate of insulating material having an opening 29 therein. Slide valve 28 is permitted a limited reciprocal vertical travel between relatively movable contacts 2 and 3 and partition 15. Preferably slide valve 28 operates pneumatically, but its travel is controlled by movement of the adjacent blade-type contact 3 and to this end blade-type contact 3 is illustrated as provided with an extension 30 whose upper end abuttingly engages the slide valve 28. In order to withstand the end pressure of blade extension 30 the insulating material of slide valve 28 is reinforced by a metal insert 31 positioned so as to engage the extension 30 on blade 3, as best shown in Figs. 1 and 8.

The end plate 10 is provided with vent opening 32 adjacent the opening 18 so that blast

pressure within chamber 13 is effective to move slide valve 28 downward during the opening movement of the circuit breaker. It will be obvious that when a blast of fluid is present in chamber 13 slide valve 28 will move in unison with movable contact 3 regardless of whether or not the blade contact 3 is being moved out from, or back into, the arc extinguishing structure 1 in accordance with circuit opening or closing operations respectively; for fluid under pressure acting on the upper end of slide valve 28 adjacent stationary contact 2 biases the valve to its down position since the lower end of slide valve 28 is freely vented to atmosphere by virtue of the opening 32 in end plate 10. When no blast of fluid is present in chamber 13, element 30 integrally formed with contact 3 will serve to move slide valve 28 toward its closed position during closing movement of contact 3 against the force of gravity acting on slide valve 28. The remaining volume within chamber 13 that is not occupied by stationary contacts 2 or blade contact 3 is completely filled with blocks of insulating material such as 33 and 34, best shown in Fig. 2. With this arrangement, a minimum of air is required since no unnecessary air spaces are present which must be filled before the blast of fluid becomes effective.

The stationary contact 2 is preferably connected to a line terminal in any suitable manner. In Fig. 1 this line terminal is schematically illustrated at 35. Similarly, the movable contact 3 may be connected to a line terminal 36 through a sliding contact or a flexible lead.

The arrangement described thus far is not capable per se of interrupting high currents and in accordance with my invention I provide in chamber 14 the zero selector device of my invention which interrupts the current with little or no arcing. This zero selector device comprises a pair of zero selector units 37 and 38 provided with hinge pins 39 and 40, respectively, so as to be pivotally mounted to the side walls 7 and 8 of the arc extinguishing structure 1, these side walls being provided with cooperating openings for hinge pins 39 and 40.

Each of the zero selecting units 37 and 38 is substantially identical and accordingly only one of these units 37 will be described in detail while the corresponding parts of the other unit are designated by the same reference numerals. As is best shown in Figs. 1 and 3, zero selecting unit 37 comprises a plurality of insulating members 41, 42, 43 and 44, each having portions thereof cut away so that when these members are fitted together as is shown in Fig. 3, they will provide a hollow space for accommodating a force coil 45. This force coil 45 comprises a strip of conducting material such as copper, as is best shown in Fig. 3, wound in the form of a coil, as is best shown in Fig. 1, with a layer of insulating material 46 also in strip form separating the adjacent layers of the coil 45. This coil is wound about a deflectable resilient core member 47. Preferably, deflecting member 47 is formed of a light but hard and strong material. I have found that a deflecting member formed of an alloy of aluminum such as is sold under the trademark of Duralumin is very satisfactory since it provides the desired lightness, strength and resiliency. The space inside of coil 45 should be sufficient to permit a small amount of deflection of deflecting member 47. This space is clearly indicated at 48 in Figs. 1, 3 and 4, the purpose

of which will become more apparent as the following description proceeds.

In order to make deflecting member 47 still lighter a plurality of holes 49, best shown in Figs. 1 and 3, are drilled longitudinally thereof. One end of deflecting member 47 is adapted to be fixedly supported in zero selecting unit 37 and to this end is provided with a pair of laterally extending ears 50, clearly shown in Fig. 7. The fixed end of deflecting member 47 is provided with a slot 51 into which one end 52 of coil 45 may be inserted and electrically connected thereto, as by welding or the like. The deflecting end of deflecting member 47 is provided with an opening 53 into which is inserted an arcing contact 54 which cooperates with a similar arcing contact 55 associated with zero selecting unit 38. Arcing contact 54 is suitably supported as by screws 56 from the free or deflecting end of deflecting member 47 and is provided with an arcing tip of arc resistant material, indicated at 57. The zero selecting units 37 and 38 including the coils 46 are provided with openings 58 through which arcing contacts 54 and 55 may extend so that arcing tips 57 may be in electrical engagement. Furthermore each of these zero selecting units 37 and 38 is provided with a cut-away portion 59.

The other end of force coil 45 indicated at 60 in Fig. 1 is preferably inserted in a slot in pin 39 and suitably welded or otherwise fastened thereto in good current carrying relationship. It will be observed that the circuit through the second set of contacts comprising arcing contacts 54 and 55 is connected across hinge pins 39 and 40 and may be traced through the force coils 45, deflecting members 47 and arcing contacts 54 and 55.

In accordance with my invention the circuit through arcing contacts 54 and 55 is connected across line terminals 35 and 36 in parallel with relatively movable current carrying contacts 2 and 3. Accordingly, hinge pin 39 is illustrated as being connected with stationary contact 2 through a terminal 61, flexible conductors 62 and a conductor bar 63. Similarly, hinge pin 40 is connected with sliding contact 25 through a terminal 64, flexible conductors 65 and conducting bar 66. It will be understood that side plate 7 will be provided with recesses for accommodating these conducting members which recesses are of sufficient size to permit limited pivotal movement of terminals 61 and 64.

In order to prevent the force coils 45 from spreading due to the magnetic forces involved, the zero selecting units 37 and 38 are reinforced by a plurality of nonmagnetic tension members 67 which extend across coils 45 and are held in position by suitable bolts 68. These tension members may be formed from any nonmagnetic material, such as brass or the like. Adjacent the fixed end of deflecting member 47 there is provided a pair of special tension members 69 and 70 best shown in Figs. 1 and 7. These tension members, also formed from nonmagnetic material, are provided with cooperating notches 71 for accommodating the lateral extensions or ears 50 of deflecting member 47 thereby fixedly anchoring this end of deflecting member 47 in each zero selector unit 37 and 38.

The zero selecting units 37 and 38 are mounted, respectively, above and below the blast opening 16 in partition 15, and substantially fill the chamber 14 as is best shown in Fig. 8. When zero selector units 37 and 38 are in the positions 75

indicated in Figs. 1, 4 and 8 arcing contacts 54 and 55 are in current carrying engagement. Normally the zero selecting units 37 and 38 are biased to the closed position indicated in Figs. 1 and 4 by means of suitable springs 72 and 73, respectively. Spring 72 is inserted through an opening 74 in end plate 9 so that one end thereof engages zero selecting unit 37. Similarly, spring 73 is inserted through an opening 75 in end plate 10 with one end thereof engaging zero selecting unit 38. The other end of spring 72 engages with a pivotally mounted member 76 having a latching arm 77 and a tripping arm 78. Pivotally mounted member 76 is hingedly supported to a member 79 suitably supported from end plate 9 as by bolts 80. The latching arm 77 of pivotally mounted member 76 extends into an opening 81 in zero selecting unit 37 so that the notch 82 thereof engages the end of deflecting member 47 whereby deflecting member 47 is normally held in the current carrying position indicated in Figs. 1 and 4. The tripping extension 78 has a portion thereof extending into chamber 14 so as to be engaged by zero selecting unit 37 upon pivotal movement in a counter-clockwise direction thereof. Such counter-clockwise direction of zero selecting unit 37 will engage the tripping extension 78 of pivotally mounted member 76 to cause counter-clockwise rotation thereof with the resultant release of the latching member 77 relative to deflecting member 47.

Similarly, the other end of spring 73 is in engagement with a pivotally mounted member 83 which also includes a latching extension 84 and a tripping extension 85 identical with extensions 77 and 78 described above. Member 83 is pivotally mounted to member 86 supported from end plate 10 as by bolts 87. Latching extension 84 extends into an opening 88 in zero selecting unit 38 so that the notch 89 thereof normally engages the end of deflecting member 47 associated with zero selecting units 38. It will be obvious from the above description that spring means 72 and 73 normally bias both the associated zero selecting units 37 and 38, respectively, and the associated latching extensions 77 and 84, respectively, into the positions indicated in Figs. 1 and 4.

An arc cutting cross barrier 90 is provided in chamber 14 and is supported from side plates 7 and 8 as by bolt 91 on the center line between zero selecting units 37 and 38. The middle portion of this arc cross barrier 90 is reduced to a V-section whose knife edge lies closely adjacent to the arcing tips 57 for dividing the extinguishing blast as is best shown in Figs. 1 and 4. The extended side portions of this arc cross barrier 90 fits snugly into corresponding cut-away portions 59 of zero selecting units 37 and 38 whereby fluid under pressure entering chamber 14 through opening 16 is substantially confined in its flow to impinge arc cross barrier 90 to the convergent-divergent passage between zero selecting units 37 and 38 and side walls 7 and 8 as is most clearly illustrated by Fig. 6.

In order to cool the arc gases flowing above and below the arc cross barrier 90, it may be desirable to provide suitable cooling means which have been indicated at 92 and 93. As is best shown in Fig. 3 the arc cooling means 93 comprises a plurality of spaced metal plates 94 suitably held together as a unit by bolts 95.

From the above description it is obvious that the current is normally carried by main contacts 2 and 3. Upon relative separation of con-

tacts 2 and 3 the current can be carried through the parallel circuit including arcing contacts 54 and 55. In order to be sure that this transfer of current is readily made it is desirable to introduce a reactance drop in the circuit of the main contacts 2 and 3. This is accomplished by surrounding the movable blade 3 with a ring of iron or other magnetic material. As is best shown in Figs. 1 and 2, insulating plate 11 is provided with an insert 96 of iron or other magnetic material, while insulating blocks 33 and 34 adjacent movable contact 3 are provided with inserts 97 and 98, respectively, also of magnetic material. The insert 31 in slide valve 28 described above, preferably is provided with an enlarged portion 31' best shown in Fig. 8, to complete the magnetic ring around blade contact 3. If desired the lower portion of insert 31 may be formed of non-magnetic material, such as brass, so that the magnetic ring around blade contact 3 is initially incomplete and therefore produces substantially no reactance. At about the time that the transfer of current through arcing contacts 54 and 55 is desired the magnetic portion 31' has moved to the position indicated in Figs. 1 and 2 to complete the magnetic ring, thereby introducing the desired reactance for causing ready transfer of the current from the main contacts 2 and 3 to the arcing contacts 54 and 55.

With the circuit breaker in the closed position the arcing contacts 5 and 6 are in current carrying engagement and in view of the impedance of force coils 45 substantially all the current flows through main contacts 2 and 3. To initiate an opening operation of the circuit breaker movable contact 3 is actuated and blast valve 20 is operated. High pressure air is admitted into the chamber 13 in the conventional manner. When movable contact 3 reaches a position so that arcing tips 5 and 6 begin to separate, the current is shunted to the parallel circuit already defined through the zero selecting units 37 and 38 with the current flowing through the force coils 45 and the deflecting members 47. It will be obvious from the drawings that a sufficiently high current flowing in force coils 45 will produce a magnetic field which reacts with the magnetic field produced by the current flowing in deflecting members 47 thereby forcing the deflecting members 47 in a direction to hold arcing contacts 54 and 55 in current carrying engagement. The magnetic ring comprising members 31', 96, 97 and 98, around movable contact 3 causes the current to be transferred to arcing contacts 54 and 55 with no arcing. As the main current carrying contacts separate slide valve 28 moves downwardly so that at the point of separation opening 29 coincides to a limited extent with opening 16 whereby a blast of air under pressure scours the main current carrying contacts 2 and 3 and enters chamber 14. As already explained, the high pressure above slide valve 28 forces the valve downward so that it closely follows movable contact 3 with stop-strip or extension 30 secured to the contact 3 in abutting engagement with the slide valve insert 31.

When the fluid or air under pressure is admitted to chamber 14 it immediately causes zero selector unit 37 to swing in a counter-clockwise direction about pivot 39 and similarly, zero selector unit 38 swings in a clockwise direction about pivot 40. Deflecting members 47, however, are held stationary for an instant by latching extensions 77 and 84 which prevent them from immediately following their associated zero se-

lector units 37 and 38, respectively. The deflected position of deflecting members 47 is shown in Fig. 5. When the zero selecting units 37 and 38 strike the tripping projections or extensions 78 and 85, respectively, the latching extensions 77 and 84 are moved out of latching engagement with deflecting members 47. This suddenly releases deflecting members 47 and the inherent stiffness thereof tends to cause them to assume their non-deflected position. If at the instant that latching extensions 77 are released the instantaneous current flowing in force coils 45 is high, members 47 will still remain deflected due to the electro-magnetic force exerted upon them by the force coils 45 so that arcing contacts 54 and 55 remain in current carrying engagement. This condition is clearly indicated by the schematic arrangement shown in Fig. 5. As the instantaneous current becomes smaller and smaller along the decline of the alternating current wave, a point is reached just ahead of the current zero of the current wave where the forces due to the stiffness of deflecting members 47 exceed the magnetic forces tending to keep them deflected and in the position indicated in Fig. 5, whereupon deflecting members 47 snap back to normal position thus separating arcing contacts 54 and 55, as is clearly shown in Fig. 6. The very insignificant arc formed between arcing contacts 54 and 55, by virtue of the fact that they did not separate precisely at the zero point of the current wave, is blasted against the sharp edge of arc splitter 90 and extinguished in the well known manner, the arc gases finally exiting through arc coolers 92 and 93.

Following the interruption of the current flow, slide valve 28 has moved down to its maximum travel position thereby again closing the opening 16 precisely in accordance with contact travel 40 to prevent the loss of unnecessary air until the main blast valve 20 subsequently closes the air supply to arc extinguishing structure 1. The blade 3 is then drawn clear of the arc extinguishing structure 1 with the fingers 26 of sliding contact 25 acting as gates to prevent the loss of air through the blade opening 18 until the main blast valve 20 is closed. Upon cessation of the blast, the pressure in chamber 14 subsides so that the zero selecting units 37 and 38 return to their biased closed latched positions, as shown in Fig. 1. The slide valve 28 remains in its lower closed position until a subsequent breaker closing operation.

The closing of the breaker is effected by contacts 2 and 3 by virtue of the fact that the slide valve 28 is in such a position if a blast of fluid under pressure is supplied during the closing stroke to permit this fluid under pressure to open arcing contacts 54 and 55. These arcing contacts are closed after the air blast is shut off.

From the above description it will be obvious that the limiting factor, as far as the interrupting ability of the circuit breaker is concerned, is the mechanical strength of the zero selecting units with respect to the magnetic forces involved. It would be desirable if zero selecting units such as 37 and 38 could be designed for application to all sizes of circuit breakers regardless of the current to be interrupted, in which event the zero selecting units would be identical for all circuit breakers. If the zero selecting units were designed to withstand magnetic forces produced by currents of the magnitude of say 40,000 amperes and below, any mag-

nitude of current above this value may be interrupted in accordance with the modification of my invention illustrated in Fig. 9. The corresponding parts of Fig. 9 are designated by the same reference numerals as in the preceding figures. The selector units 37 and 38 are identical with the selector units described above. It is assumed by way of example, that the selector units 37 and 38 are designed to satisfactorily withstand the magnetic forces involved with currents up to and including 40,000 amperes. In accordance with my invention disclosed in Fig. 9, I provide an auxiliary zero selecting unit 99 in the form of a loop of resilient current conducting material in between conductor 63 and zero selecting unit 37. Similarly, an auxiliary zero selecting unit 100 is connected between conductor 66 and zero selecting unit 38. Zero selecting units 99 and 100 are designed so that with current exceeding 40,000 amperes flowing therethrough they close associated contacts 101 and 102, respectively. Contacts 101 and 102 are interconnected by an impedance generally indicated at 103 which is substantially the same as the impedance of the circuit through zero selectors 37 and 38. If a current of 80,000 amperes is shunted through conductors 63 and 66 upon opening of main current carrying contacts 2 and 3, contacts 101 and 102 will be closed and the 80,000 amperes will divide so that 40,000 amperes flow through impedance 103 and 40,000 amperes flow through selector units 37 and 38. As soon as the instantaneous alternating current decreases below 40,000 amperes contacts 101 and 102 open automatically and zero selector units 37 and 38 will then function to interrupt the circuit at substantially the zero point with little or no arcing. The proportion of the current carried by impedance 103 and zero selecting units 37 and 38 is determined by their relative impedances and may be arranged according to the maximum interrupting capacity required. It should be understood that additional auxiliary zero selecting units may be provided for shunting still higher proportions of the total current flowing in the circuit so that the zero selecting interrupting units 37 and 38 are never permitted to carry current in excess of their predetermined current rating.

While I have shown and described particular embodiments of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. In a fluid blast circuit breaker, an arc extinguishing chamber, a pair of relatively movable contacts associated with said chamber, a source of fluid under pressure, means including a blast valve interconnecting said source and said chamber, and an auxiliary slide valve formed of insulating material and having a surface against which fluid supplied to said chamber when said blast valve is open exerts a force to cause said slide valve to press against one of said contacts, said slide valve being operable in response to movement of said one contact for preventing a blast of fluid from extinguishing said arc even though said blast valve is opened, until a predetermined movement of said one contact has occurred.

2. In a fluid blast circuit breaker, an arc extinguishing chamber, a pair of relatively movable contacts associated with said chamber, a source of fluid under pressure, means including a blast valve interconnecting said source and said chamber, means defining a large opening into said chamber and an auxiliary slide valve containing an aperture therein said opening and aperture being out of registry during the closed position of said breaker so that no fluid under pressure may be supplied to said chamber even though said blast valve is opened, and means including said fluid under pressure for causing said slide valve to move in response to movement of one of said contacts to supply a blast of fluid to said chamber by registry of said opening with said aperture upon a predetermined movement of said one contact.
3. In an electric circuit interrupter for alternating current circuits comprising a pair of main current carrying contacts, a pair of auxiliary contacts, means for transferring the current from said current carrying contacts to said auxiliary contacts during a circuit interrupting operation, a pair of pivotally mounted zero selector units one associated with each of said auxiliary contacts, each of said zero selector units comprising a deflecting member supporting its associated auxiliary contact and a force producing winding connected in series with said associated auxiliary contact and closely associated with said deflecting member, means for latching said auxiliary contacts in the closed position, means for causing pivotal movement of said zero selector units, and means responsive to pivotal movement of said zero selector units for releasing said latching means, said force coils causing said associated deflecting members to deflect and hold said auxiliary contacts in engagement until a predetermined low value of instantaneous current is attained, the resilience of said deflecting members causing high speed separation of said auxiliary contacts at substantially current zero.
4. In an electric circuit interrupter for alternating current circuits comprising a pair of main current carrying contacts, a pair of auxiliary contacts, means for transferring the current from said current carrying contacts to said auxiliary contacts during a circuit interrupting operation, a movably mounted zero selector unit associated with one of said auxiliary contacts comprising a deflecting member supporting said one auxiliary contact and a force producing winding connected in series with said one contact, means for latching said auxiliary contacts in the closed position, means for causing movement of said zero selector unit, and means responsive to movement of said zero selector unit for releasing said latching means, said force coil causing said deflecting member to deflect and hold said auxiliary contacts in engagement until a predetermined low instantaneous current value approaching zero is attained.
5. In an electric circuit interrupter for alternating current circuits comprising a pair of main current carrying contacts, a pair of auxiliary contacts, means for transferring the current from said current carrying contacts to said auxiliary contacts during a circuit interrupting operation, a pivotally mounted zero selector unit associated with one of said auxiliary contacts comprising a deflecting member supporting said one auxiliary contact and a force producing winding connected in series with said one auxiliary con-

tact, means for latching said auxiliary contacts in the closed position, means for causing pivotal movement of said zero selector unit, and means responsive to pivotal movement of said zero selector unit for releasing said latching means, said force coil causing said deflecting member to deflect and hold said auxiliary contacts in engagement until a predetermined low instantaneous current value approaching zero is attained.

6. In an electric circuit interrupter for alternating current circuits comprising a pair of relatively movable contacts, a movably mounted zero selector unit associated with one of said contacts comprising a deflecting member for supporting said one contact and a force producing winding connected in series with said contact, means for latching said contacts in the closed position, means for moving said zero selector unit, and means responsive to movement of said zero selector unit for releasing said latching means, said force coil causing said deflecting member to deflect and hold said contacts in engagement until a predetermined low instantaneous current value is attained.

7. In an electric circuit interrupter for alternating current circuits comprising a pair of relatively movable contacts, a movably mounted zero selector unit associated with one of said contacts comprising a deflecting member for supporting said one contact and a force producing member connected in series with said contact, means for latching said contacts in the closed position, fluid means for moving said zero selector unit, and means responsive to movement of said zero selector unit for releasing said latching means, said force producing member causing said deflecting member to deflect and hold said contacts in engagement until a predetermined low instantaneous current value is attained.

8. In an electric circuit interrupter for alternating current circuits comprising a pair of relatively movable main current carrying contacts, a pair of relatively movable auxiliary contacts, means for transferring the current from said current carrying contacts to said auxiliary contacts during a circuit interrupting operation comprising an incomplete ring of magnetic material surrounding a movable one of said main contacts, and means movable with said one contact for completing said ring of magnetic material.

9. In an electric circuit interrupter for alternating current circuits, a pair of relatively movable contacts, a zero selector unit associated with one of said contacts and normally holding it in a closed position, said zero selector unit comprising a deflecting member for supporting said one contact, an electro-magnetic means also tending when energized to hold said contacts in the closed position, and means for moving said zero selector unit in a direction to open said contacts, said deflecting member permitting such movement while said electro-magnetic means holds said contacts closed for instantaneous current values therein in excess of a predetermined value.

10. In an electric circuit interrupter for alternating current circuits, a pair of relatively movable contacts, a zero selector unit associated with one of said contacts and normally holding it in a closed position, said zero selector unit comprising a deflecting member for supporting said one contact, an electro-magnetic means also tending when energized to hold said contacts in the closed position, and means for moving said

zero selector unit to deflect said deflecting member without opening said contacts until a predetermined low value of instantaneous current is attained in said electro-magnetic means.

11. In an electric circuit interrupter for alternating current circuits, a pair of relatively movable contacts, a zero selector unit associated with one of said contacts and normally holding it in a closed position, said zero selector unit comprising a deflecting member for supporting said one contact, an electro-magnetic means also tending when energized to hold said contacts in the closed position, and fluid means for moving said zero selector unit to deflect said deflecting member without opening said contacts until a predetermined low value of instantaneous current is attained in said electro-magnetic means.

12. In an electric circuit interrupter for alternating current circuits comprising a pair of relatively movable contacts, a zero selector unit associated with one of said contacts comprising a deflecting member for supporting said one contact and a force producing member connected in series with said contact, means for latching said contacts in the closed position, fluid means for releasing said latching means, said force producing member causing said deflecting member to deflect and hold said contacts in engagement until a predetermined low instantaneous value of current is attained.

13. In an electric circuit interrupter for alternating current circuits comprising a pair of relatively movable contacts, a zero selector unit associated with one of said contacts comprising a deflecting member for supporting said one contact, and an elongated coil having substantially straight sides connected in series with said deflecting member and contact, said coil being so positioned with respect to said deflecting member that the electro-magnetic force produced by the interaction of said coil and said deflecting member is such as to tend to hold said one contact in its closed position.

14. In an electric circuit interrupter for alternating current circuits comprising a pair of relatively movable main current carrying contacts, a pair of relatively movable auxiliary contacts, means for transferring the current from said main current carrying contacts to said auxiliary contacts during a circuit interrupting operation comprising an incomplete band of magnetic material partially surrounding a movable one of said main contacts when said main current carrying contacts are closed, and means for substantially completing said band of magnetic material when said main current carrying contacts are being opened.

15. In an electric circuit interrupter for alternating current circuits, a pair of relatively movable contacts, a zero selector unit associated with one of said contacts normally holding it in the closed position, said zero selector unit comprising a deflecting member for supporting said one contact, an electro-magnetic means also tending when energized to hold said one contact in the closed position, means for moving said zero selector unit to deflect said deflecting member without opening said contacts until a predetermined low value of instantaneous current is attained in said electro-magnetic means, and means responsive to the flow of a predetermined high value of current through said circuit interrupter for bypassing a predetermined portion of said current around said zero selector unit.

16. In an electric circuit interrupter for alternating current circuits, a pair of relatively mov-

able contacts, a zero selector unit associated with one of said contacts normally holding it in the closed position, said zero selector unit comprising a deflecting member for supporting said one contact, an electro-magnetic means also tending when energized to hold said contacts in the closed position, means for moving said zero selector unit to deflect said deflecting member without opening said contacts until a predetermined low value of instantaneous current is attained in said electro-magnetic means, and electro-magnetic means responsive to the flow of a predetermined high value of current through said circuit for bypassing a predetermined portion of said current around said zero selector unit.

17. In an electric circuit interrupter for alternating current circuits, a pair of relatively movable contacts, a zero selector unit associated with each one of said contacts normally holding said contacts in the closed position, said zero selector units comprising a deflecting member for supporting the associated contact, an electro-magnetic means for each selector unit also tending when energized to hold said contacts in the closed

position, means for moving said zero selector units to deflect said deflecting members without opening said contacts until a predetermined low value of instantaneous current is attained in said electro-magnetic means, a normally open circuit having substantially the impedance of said zero selector units connected in parallel with said units, and means responsive to the flow of a predetermined high value of current through said circuit interrupter for closing said normally open circuit to bypass a predetermined portion of said current around said zero selector units.
